BOTTLE

Roy W. Dike, Wheeling, W. Va., assignor to Continental Can Company, Inc., New York, N.Y., a corporation of New York

Application July 8, 1958, Serial No. 51,698

Term of patent 14 years

(Cl. D58—6)

Figures 3, 4, 5 and 6 are horizontal sectional views thereof taken on the lines 3—3, 4—4, 5—5 and 6—6, respectively, of Figure 1.

The side and end of the bottle not shown in Figures 1 and 2 respectively, are the same as the side and end shown in said figures.

I claim:

The ornamental design for a bottle, as shown and described.
